(57) **CLAIM**

The ornamental design for a light fitting, as shown and described.

DESCRIPTION

FIG. 1 is a top perspective view of the present light fitting;

FIG. 2 is a top view of same;

FIG. 3 is a bottom view of the light fitting of FIG. 1;

FIG. 4 is a bottom perspective view of the light fitting of FIG. 1;

FIG. 5 is a front view of same, the rear view being identical;

FIG. 6 is a left side view of same;

FIG. 7 is a right side view;

FIG. 8 is an alternate bottom view of the present light fitting with a bulb shown in broken lines; and,

FIG. 9 is an alternate bottom perspective view with a bulb shown in broken lines.

The broken lines illustrate environmental structure and form no part of the claimed invention.
